ROD CHARGING MACHINE

John Willis Garrow, Copper Cliff, Ontario, Canada, assignor to The International Nickel Company, Inc., New York, N. Y., a corporation of Delaware

Application September 21, 1944, Serial No. 555,120
In Canada August 3, 1944

3 Claims. (Cl. 198—26)

1

The present invention relates to devices for charging grinding mills with grinding medium, and, more particularly, to a device for charging rods to rod mills of the "Marcy" type.

As those skilled in the art know, the comminution of ores is carried out in mills such as hammer mills, ball mills and rod mills.

The present invention relates particularly to comminuting devices of the rod mill type. Such mills consist briefly of a hollow cylindrical body disposed horizontally and provided with means for rotating the cylindrical body on its horizontal axis, and a grinding charge which consists of rods of suitable material, usually of steel. The mills vary in length and diameter and, in many instances, are from 15, 18 to 20 feet in length. The grinding medium is charged into the mill in the form of rods of such length as to rest on the inner periphery of the horizontal cylinder which is the rod mill body. These rods when charged are slightly shorter in length than the interior length of the rod mill and are usually 2.5 to 3 inches in diameter.

As might be expected, and as is well known, in grinding the ore the rods are reduced in diameter and at intervals additional rods must be charged into the mill in order to keep the weight of the grinding medium at a predetermined optimum. Heretofore, the charging of these grinding rods into the rod mill has been accomplished generally, and in fact usually, by hand. This involves heavy manual work since each rod weighs about 250 pounds and is about 15 feet long. In many operations it is customary to charge 25 rods of such dimensions and weight into each of a series of mills at regular intervals. It has been found that when a charge of 25 rods is introduced manually into a rod mill, a crew of nine men is required who take five minutes to manually charge a normal load of 25 rods and thereafter require a rest period of 3 minutes. In other words, the manual charging cycle consists of a total of 8 minutes, or a total of 72 man minutes.

By means of the present device it is possible to charge the same weight of grinding medium, i. e. 25 rods of about 250 pounds each, with a crew of three men in about 4.2 minutes, a total of 12.6 man minutes. Thus, the present device has several advantages, among which are the following:

1. A reduction in labor of about 80%.
2. An increase in labor efficiency due to the elimination of extremely heavy manual work.
3. Improved safety practice since frequent

2

minor accidents result from manual handling of the heavy rods.

It is an object of the present invention to provide a motorized device for charging grinding medium to rod mills.

It is another object of the present invention to provide a device having a runway along which individual rods are conveyed with sufficient velocity to be discharged into the mill.

10 It is a further object of the present invention to provide a means whereby the longitudinal or endwise path of travel of the rod is controlled and maintained in substantially the same plane as during its travel on the runway-conveyor during discharge into the mill until the rod has completely entered the mill.

Other objects and advantages will become apparent from the following description taken in conjunction with the drawings in which—

20 Figure 1 illustrates a side elevation of a device embodying the principles of the present invention;

Figs. 2 and 3 are vertical sections taken at lines 2—2 and 3—3, respectively, of Figure 1;

25 Fig. 4 depicts a section taken on line 4—4 of Fig. 3 showing certain parts in detail;

Fig. 5 is a more detailed view of the rod selecting means and operating control in the preferred form;

30 Fig. 6 is a plan view of the rod feeding device of my invention; and

Fig. 7 is a diagrammatic side elevation of the rod feeding device of my invention and of the rod mill showing their relative positional disposition.

35 Generally stated, the machine embodying the principles of the present invention provides means for moving single rods longitudinally along a runway with sufficient velocity to be charged into a rod mill. The machine preferably consists of a rack to hold the rods, a horizontal rod runway and conveyor, a rod selector, and a drive and power assembly for a V-belt conveyor. The whole combination is built as a portable unit supported by a steel frame mounted on swivel casters. The horizontal runway contains a plurality of grooved rollers in a single line which carry a V-belt over which the rods move to the mill. The V-belt also serves as the driving means from a motor pulley. The arc of contact of the belt with the pulley may be and generally is increased by the use of a snub-pulley.

40 Tension is maintained on the driving belt by this snub pulley and by means of pivoting the motor base, although other means known to those

skilled in the art may be employed. When tension is maintained on the driving belt by pivoting the motor, it is desirable to provide a support upon which the motor may rest in the event that the driving belt breaks. The framework carrying the belt-driven pulleys extends beyond the main supporting framework of the machine and this extending framework is preferably a continuation, in the direction of endwise travel of the rods, of the pulley-carrying framework. It is thus in substantially the same plane as the runway conveyor and, being co-extensive with the pulley-carrying framework, requires no vertical supports. It may thus be adapted to actually project through the charging port of the rod mill. This extending framework carries one or more rotatably-mounted pulleys which may be grooved similarly to the belt-driven pulleys or they may have a plane smooth face. This rotatably-mounted pulley or pulleys forms an extension of the runway conveyor and rotation is imparted by the end-wise progress of the conveyed rod. A similar rotatable pulley is mounted on a bracket vertically above the plane of the runway conveyor and so disposed that the most outwardly disposed of the rotatably mounted pulleys in the extending framework acts in fulcrum arrangement with the bracketed pulley on the progressing rod when the rod has practically completed its endwise travel. This feature is explained in greater detail hereinafter with reference to Fig. 7 of the drawings.

The rods are placed on a rod rack in any suitable manner as, for example, by means of a crane. The rack preferably is slightly higher than the runway-conveyor and preferably inclined towards it. Suitable means fixed rigidly at each end of an operating shaft parallel to the runway are provided to move one rod at a time on to the horizontal runway. Means are provided to stop the cross movement of the rod as it rolls from the rack to the runway. Means are also provided to raise the mill end of the frame off the swivel casters and hold the unit stationary during charging operations.

The foregoing description describes in a general way a machine embodying the principles of the present invention. For the purpose of giving those skilled in the art a better understanding of the invention, a more detailed description of a specific embodiment of the invention will now be given in connection with the drawings.

The machine comprises a steel frame 1 constructed of suitable material which possesses sufficient strength together with lightness. Thus, for example, the frame may be constructed of angle iron, steel, and the like of suitable thickness and width to support the maximum load to be imposed upon it and to withstand the stresses to which it is subjected. In order to provide a mobile device, the frame is mounted on a suitable number of swivel casters 2. At a suitable vertical height a pair of horizontally disposed beams 5 are provided which serve as supports for grooved pulleys 7 and 8 and pulley 9, which may be grooved or smooth faced, at the mill-end of the machine. Grooved pulleys 7 and 8 are driven by a V-belt 11, as is more fully described hereinafter. When the distance between the mill end of the conveyor and pulley 8 is great, one or more additional pulley or pulleys 21, rotatably mounted and driven only by passage of the rod thereover, may be installed between pulleys 7 and 8 as shown in Fig. 7. A depressing pulley 4 is provided at a suitable distance from

the mill end of the device. Pulley 4 ensures that the longitudinal or endwise path of travel of the rod is controlled and maintained in substantially the same plane as during its travel on the runway-conveyor while being charged into the mill so that the rods do not tend to pile up in the mill like so many jack straws. Journaled in beams 5 are shafts 6 upon which belt driven grooved pulleys 7 and 8 are mounted. Grooved pulleys 8 and 7 are driven by V-belt 11 which passes over motor pulley 10 of the motor 9, to and over pulley 8, thence to and over pulley 7, around snub pulley 25 and completing its circuit around pulley 10. The grooved pulleys 7 and 8 have their grooved surfaces in two planes as shown more clearly in Fig. 2 and Fig. 5, and form a lower groove for the V-belt in which the angle of the sides is determined by the particular V-belt used in the manner well known in the art. Co-extensive with this lower groove, an upper groove is formed having its angular sides at the same or a different angle to the angle of the lower groove sides. The upper surface of the V-belt 11, when in place, forms the base of this upper groove and this upper surface of the V-belt, cooperating with the angular sides of the upper groove, forms the horizontal rod runway and conveyor 12. It is an important feature of the present invention that the rods shall be adequately supported while on this runway and in its preferred form it shall be such that the rod will be in substantially tangential contact with the angular sides of the upper groove while resting on and supported by the outer surface of the V-belt. The angle of inclination of the sides of the upper groove will thus be determined by the need for obtaining this three-point contact between the rod being carried and the rod runway and conveyor 12.

At suitable places along the upper edge of the beams 5, rod stops 13 are provided to prevent discharge of the rods over the side of the machine. A rod rack 14 is disposed in a plane slightly higher than the top of V-belt 11 so that the rods will roll on to the V-belt. It is quite essential that a V-belt of this type be used in order that an instantaneous velocity shall be applied to the rods the instant they roll on to the belt conveyor surface 12. This belt also functions or serves the purpose of reducing the wear on the grooved pulleys 7 and 8 which are largely used to guide the rods along the path into the mill.

In order that one rod at a time shall be discharge on to the runway-conveyor 12, a suitable mechanism, such as the star wheels 15 mounted on operating shaft 16, is provided. The star wheels 15 are rigidly mounted on the opposite ends of shaft 16 and are controlled by a manually operated lever 17 at the mill end of the rack which turns shaft 16 by engaging a ratchet 18 fixed on the shaft and thereby controls the movement of the rods to the runway 12. A brake lever 19, at the same location as lever 17, and also manually operated, checks the rotation of the star wheels 15 allowing one rod at a time to be fed to the charging machine. The details of this star wheel, as well as its positional disposition in relation to the runway conveyor and the rod rack, are shown in Fig. 5. It will be clearly seen in this view that one of the rods is engaged in one of the selector notches 28 of the star wheel 15 and that a selector notch 30 on approximately the opposite side of the star wheel is engaged by the semicircular dog on brake lever 19. It will also be apparent that counter-clockwise rota-

tion of the star wheel through approximately 72° will remove the selected rod vertically out of the path of gravitational flow and will discharge it, as shown at 29, onto the runway-conveyor 12. By the same rotation the following selector notch will select the following rod and, on the opposite side of the star wheel, the following notch will be engaged by the dog on brake lever 19. It will be apparent that the star wheel, in addition to functioning as a rod selector means, also serves to positively arrest the gravitational flow of the rods on the rod rack 14 while one of said rods is in selected position and to interrupt that flow during the rotative discharging step. In the view of the star wheel shown in Fig. 2, the rotation of the star wheel has been interrupted at the point of highest vertical movement of the selected rod. It will be seen in this view that a continuation of the rotation of the star wheel in a clockwise direction will discharge the selected rod onto the runway-conveyor 12 and that a new rod will be selected from the rod rack 14. While the preferred embodiment of the present invention contemplates the removal of the selected rod from the selective position and the discharging of it onto the run-way conveyor in one, uninterrupted rotational step, it is apparent from the view shown in Fig. 2 that the insertion of an intermediate step between the step of selecting and discharging would not constitute a departure from the principles of the present invention. A jack handle 20 connected to a shaft 21 by links 22 operates cams 23 and jack legs 24 to raise the mill end of the frame off the swivel casters and hold the unit stationary during charging operations.

In charging a rod mill, the machine is moved into position and the jacks lowered by means of the jack handle 20. Rods to be charged are placed by a crane on the rack. The rods lie longitudinally on the rack and, because of the side slope, move in turn across the rack and enter notches on the star wheel rod-selecting means in the manner described heretofore. The next partial turn of the star wheel moves this rod vertically out of the path of lateral gravitational movement of the rods and discharges the rod selected onto the runway conveyor. This will be apparent from the arrangement shown in Figs. 5 and 6 of the drawings. The rod is guided into the groove of the rollers by angle stops 13. The V-belt 11 with grooved pulleys 7 and 8 acts as a runway-conveyor and the rod is conveyed along the runway with sufficient velocity to be discharged into the mill. The driving speed of the V-belt or other carrying medium may be varied to deliver rods into the mill door opening at any desired speed. The runway 12 comprising pulleys 7 and 8 and belt surface 11 is not necessarily horizontal, but may be inclined so that the rods can be discharged at locations higher or lower than the feed position of the rods into the grooved rollers.

Fig. 6 is a plan view of the machine showing the relative position of the plurality of rods on the rod rack, one of the rods that has been selected out of the path of lateral gravitational movement of the plurality of rods and one of the rods in its initial position on the runway-conveyor. It will be noted from the view shown in this figure of the drawings and from the foregoing description of Fig. 5 and Fig. 2 that the star wheel selecting means 15 serves to positively arrest the lateral movement of the rods on the rod rack while one of said rods is in selected position and to interrupt

that movement during the rotative rod discharging step.

Fig. 7 shows a diagrammatic side elevation of the machine of the present invention in its relation to the rod mill being charged with rods. In this view, one of the rods 31 has left the driven portion of the runway-conveyor 12 and is supported in approximately the same plane of travel by the rotatably mounted pulleys 3 and 4 carried by the extending framework. It will be apparent from this view and from the view shown in Figure 1 that this extending framework comprises an extension of the horizontally disposed beams 5. As has been stated earlier, however, this framework is not necessarily horizontal, but may be inclined towards the rod mill 26. The pulley 4 is in the same vertical plane as pulley 3 and, as in the view shown in Fig. 7, prevents the rod from toppling endwise into the rod mill, the pulley 3 serving in fulcrum arrangement against the overhanging weight of the rod. Pulley 27 is shown supported on the extending framework and disposed between pulley 3 and driven pulley 8. This pulley 27, with pulley 3, serves as a continuation of the runway-conveyor. When the size or weight of the rod being handled, or when the extending framework is of considerable length, additional rotatably mounted pulleys may be installed in this continuation of the runway-conveyor. The rod mill as shown in this view has been partly broken away in order to show the rod in the position described.

Although the present invention has been described in conjunction with a specific embodiment thereof, those skilled in the art will understand that variations and modifications thereof may be made. Such variations and modifications are to be considered within the purview of the specification and the scope of the appended claims.

I claim:

1. In a machine for feeding cylindrical rods of substantial length longitudinally into a machine of the rod mill type, the combination of a roller rack having a rod-supporting means of sufficient lateral inclination to impart lateral rolling movement to a plurality of rods supported thereon, a runway-conveyor disposed transversely of said rod-supporting means beyond and slightly below the lower extremity of inclination of said rod-supporting means, vertical stop means beyond but closely adjacent said runway-conveyor whereby lateral movement of said rods beyond said conveyor is prevented, and rod-transfer means projecting upwardly into the path of said rolling movement intermediate said supporting means and said runway-conveyor whereby said rolling movement is normally arrested, said rod-transfer means comprising a shaft rotatably mounted parallel to said rods, a plurality of substantially circular members rigidly mounted at substantially opposite ends of said shaft and within said path, said members having a plurality of notched indentations at spaced intervals in the peripheries thereof whereby the lowermost rod on said rod-supporting means is engaged in an aligned pair of said indentations and on rotation of said shaft in the direction of said path is removed upwardly out of said path and is discharged onto said runway-conveyor, said runway-conveyor consisting of a supporting framework extending across said path transversely of said rod-supporting means and therebeyond on one side thereof toward said mill, a pair of pulleys and at least a third pulley carried by said framework and

adapted for in-line rotation, said pair of pulleys being disposed at approximately the opposite sides of said rod-supporting means, a V-belt driving said pair of pulleys and presenting a conveyor surface moving endwise to said lateral movement and towards said mill at a substantially greater rate of linear movement than the rate of lateral movement whereby, through a high degree of frictional engagement, immediate and positive longitudinal movement is imparted to said discharged rod, means adapted for locking engagement with at least one of the notched indentations in said circular members between successive discharging steps, means cooperating with said third pulley for guiding said discharged rod throughout the latter part of said longitudinal movement and means for retaining said rack at rest during said steps.

2. In a machine for projecting cylindrical rods of substantial length longitudinally through a charging port into a machine of the rod mill type, the combination of a rack having a rod-supporting means of sufficient lateral inclination to impart lateral rolling movement to a plurality of rods supported thereon, rod-transfer means disposed transversely of said rod-supporting means at the lower extremity of inclination thereof, said rod-transfer means consisting of a rotatably mounted shaft parallel to said rods, at least a pair of substantially circular members rigidly secured in spaced-apart relationship to said shaft and projecting upwardly into the path of lateral movement of said rods whereby said movement is normally arrested, a plurality of aligned rod-engaging means peripherally disposed in said circular members wherein the lowermost of said rods is positively engaged with said arresting of movement, means for rotating said shaft whereby said engaged rod is moved upwardly out of said path and the succeeding rod is engaged in successive rod-engaging means, a runway-conveyor disposed transversely of said rod-supporting means onto which said first engaged rod is discharged on further rotation of said shaft, vertical stop means adjacent said runway-conveyor on the side opposite to that of said rod-transfer means whereby further lateral movement of said discharged rod is positively arrested, and means adapted for locking engagement with said rod-

engaging means between successive discharging steps, said runway-conveyor consisting of a supporting framework extending outwardly beyond said rack and to the charging port of said mill, a pair of grooved pulleys carried by said framework and adapted for rotation directionally lengthwise thereof, a V-belt driving said pair of pulleys and presenting a conveyor surface moving at a substantial rate of linear movement toward said mill whereby said discharged rod is projected along said runway-conveyor, a third grooved pulley rotatably carried on said framework adapted to carry said projected rod during the latter stages of said projection, and a rotatable member above said third pulley cooperating therewith to maintain said projected rod in substantially the plane of original projection during said latter stages.

3. In a machine for projecting cylindrical rods of substantial length longitudinally through a charging port into a machine of the rod mill type, the combination of a rack having a rod-supporting means of sufficient lateral inclination to impart lateral rolling movement to a plurality of rods supported thereon, a runway-conveyor disposed transversely of said rod-supporting means at the lower extremity of inclination thereof, said runway-conveyor consisting of a supporting framework integral with said rack and extending laterally therebeyond to said port, a pair of grooved pulleys rotatably supported on said framework and adapted for rotation directionally lengthwise thereof, a V-belt driving said pair of pulleys and presenting a conveyor surface moving at a substantial rate of linear movement toward said mill, rotative rod-transfer means intermediate said rod-supporting means and said runway-conveyor adapted to remove said rods individually from said rod-supporting means and to rotatively transfer said removed rods to said conveyor surface whereby projectional lengthwise movement is imparted to said transferred rods, vertical stop means adjacent said runway-conveyor adapted to positively prevent lateral movement of said transferred rods beyond said runway-conveyor subsequent to said transfer, and means adapted for locking engagement with said rotative-transfer means between successive rotative transfer steps.

JOHN WILLIS GARROW.
